SLIP-OFF INGOT

Albert H. Jung, Flushing, N. Y., assignor to
United American Metals Corporation, Brooklyn, N. Y., a corporation of New York

Application July 21, 1938, Serial No. 220,535

4 Claims. (Cl. 22—218)

This invention relates to metal ingots and more particularly to ingots of the type that are fed gradually into a melting pot by an automatic feeder.

Prior to my invention ingots of such configuration and characteristics as to be adapted for use with automatic feeders of the "Margach" type for example have been devised. The "Margach" feeder among other elements of equipment includes an endless chain to which may be attached at intervals a series of hooks adapted to receive a series of ingots to be fed to the melting pot. One ingot for use with the "Margach" feeder comprises simply an elongated bar, perforated near one of its ends in a manner to permit its being threaded onto one of the hooks of the feeder. Further, prior to my invention, ingots have been designed of such configuration as to automatically slip off the hook of the feeder when the ingot being fed to the molten bath has descended to a level at or above the lower portion of a slot formed in the upper end of the ingot. Such ingots have been termed slotted-eared ingots. Such slotted-eared ingots while they facilitate the feeding of the ingots by the feeder into the molten bath with little attention from the operator during the feeding process, are relatively difficult to thread onto the feeder prior to the feeding operation. Applicant has devised a new ingot of such proportions and configuration as to facilitate the "loading" of the feeder prior to the feeding operation.

It is an object of the invention to provide a slip-off ingot suitable for use with the "Margach" type or other feeders which is relatively rugged and facilitates the loading of the feeder.

It is a further object of the invention to provide a slip-off ingot having each end so formed as to permit either end to be engaged with a "Margach" type or other feeder by a relatively simple operation.

Other objects and the nature and advantages of the invention will be apparent from the following description taken in conjunction with the accompanying drawing, wherein:

Fig. 1 is a view in perspective of an ingot in accordance with my invention;

Fig. 2 is a cross sectional view taken along lines 2—2 of Fig. 1 and looking in the direction of the arrows;

Fig. 3 is a fragmentary view in perspective, approximately full size of an ingot attached to a feeder ring of an automatic feeder;

Fig. 4 is a side elevation illustrating the feeding of the ingot into the melting pot; and,

Fig. 5 is a view similar to Fig. 4 but with the feeding operation substantially completed, the ingot having slipped off the ring of the feeder.

Referring to the drawing, an ingot 10 comprising an elongated body portion 11 having a section 12, as illustrated in Fig. 2, is formed at each of its ends 13 and 14 with a hook like configuration 15 and 16 adapted to be associated with the feeder hook ring 17 as illustrated in Figs. 3 and 4. The ends 13 and 14 of the ingot bar 10 between the hook portions 15 and 16 and the body portion 11 have reduced portions 18 and 19, each of which are adapted to be grasped by the operator during the loading operation, or during the storing, packing, or shipping of the ingots. It is apparent from the illustration that the portions 18 and 19 being situated as they are, are handy places for the operator to hold the ingot with a minimum of slippage, for if the operator will pull outwardly, the hooks 15 and 16 will become engaged.

In the preferred form, the side 20 of the ingot bar 10 which is remote from the side 21, at the ends of which the hooks 15 and 16 are formed, is substantially unbroken in configuration throughout the entire length of the ingot. The side 21 at each end is formed with recessed portions 22 and 23, respectively, which recessed portions extend to approximately one-half the distance from the side 21 to the side 20 to form the hook ends 15 and 16, respectively.

When associating the ingot 10 with the hook ring 17 of the feeder chain 24, the ingot may be simply swung laterally toward the ring with one of the hook ends 13 or 14 slightly higher than the ring, great accuracy being unnecessary, until contact is made. Then, the ingot is lowered and simultaneously the hook end will engage the ring 17 as illustrated in Fig. 3. When the feeding machine has been completely loaded and operation begun, the ingot will be fed into the melting pot as illustrated in Fig. 4 until the ingot has been lowered to a level corresponding to the reduced portion 19 for example. When the feeding process has proceeded this far, the unmelted remaining portion of the ingot will tilt, or rotate, in a clockwise direction, see Figs. 4 and 5, by virtue of the fact that the center of gravity of the said unmelted remaining portion is off center, until the remaining portion of the ingot slips off completely from the hook ring into the melting pot to complete the feeding of the ingot to the bath. The feeding machine will then feed a second of a series of ingots to the bath in a similar manner and the cycle will be repeated.

It will be seen from the above that I have pro-

vided a relatively rugged, simple, slip-off type of ingot which permits of ready loading of automatic feeders of the "Margach" type feeder, for example. It will further be understood that I have provided a slip-off ingot of such configuration and characteristics as to permit of ready handling for shipping and storing.

As slip-off ingots, depend, for their association with automatic feeders, upon the configuration of their ends, any injury to same will prevent this necessary association. Accordingly, breakage at the end during handling, shipping or otherwise, prevents this association and necessitates recasting of the ingot, makes for delay, and is otherwise objectionable. Hence, each end of the ingot has been so formed as to permit of association with the hook ring of the feeder chain whereby even though one end is injured so as to prevent it being hooked through the hook ring, the other end may be so associated with the feeder hook ring. The particular configuration, then, at each end of the ingot performs the dual function, of first, facilitating handling, and second, effects the saving of time when one end is injured.

While it is conceivable that ingots in accordance with my invention might be cut to shape, I prefer to cast them in a mold with the hook portions pointing in a horizontal direction, sufficient draft having been provided as indicated in the section illustrated in Fig. 2.

Though the ingot bar 10 has been described as having end portions 13 and 14 including hook like configurations 15 and 16 and reduced portions 18 and 19, it is to be understood that the portions of the ends 13 and 14 may also be denoted by the terms nose part and base part. For example, the projecting portion to which the reference numeral 16 has been applied may be called the nose part of the end 14 and the reduced portion 19 may be called the base part of the end 14 and further, the reference numeral

14 may generally denote the entire hooked end including the portion 19 and the portion 16.

It will be obvious to those skilled in the art that various changes may be made in this device without departing from the spirit of the invention and therefore the invention is not limited to what is shown in the drawing and described in the specification but only as indicated in the appended claims.

I claim:

1. A slip-off ingot of the type suitable for use with an automatic type metal feeder and adapted to be substantially vertically suspended, said ingot comprising an elongated body portion and a hook shaped end portion for engaging the feeder, the center of gravity of the mass of the hook shaped end portion being so laterally remote from the longitudinal axis of the body portion as to effect an unbalancing of the hook end with relation to the feeder when the body portion has melted from the ingot, whereby a feeder ingot engaging element associated with the said feeder may readily be threaded by said ingot end with the assurance that upon melting of the ingot up to the ingot end, the said ingot end will automatically disengage itself from the feeder.

2. An ingot as in claim 1, having symmetrical ends whereby the loading of said feeder may be facilitated.

3. A slip-off ingot of the type suitable for use with an automatic type metal feeder, said ingot comprising an elongated body portion and a hooked end portion, said hooked end portion including a base part and a nose part, said base part being heavier than said nose part, whereby when said ingot body portion has been melted, said base part will overbalance said nose part and automatically disengage itself from the feeder.

4. An ingot as in claim 3 having symmetrical ends whereby the loading of said feeder may be facilitated.

ALBERT H. JUNG.
